UNITED STATES PATENT OFFICE.

JAMES MECREDY MACLULICH, OF LONDON, ENGLAND, ASSIGNOR TO THE SIRDAR RUBBER COMPANY, LIMITED, OF SAME PLACE.

DESIGN FOR A METALLIC WHEEL-RIM.

SPECIFICATION forming part of Design No. 35,075, dated September 10, 1901.

Application filed June 15, 1900. Serial No. 20,483. Term of patent 14 years.

To all whom it may concern:

Be it known that I, JAMES MECREDY MACLULICH, gentleman, a subject of the Queen of Great Britain, residing at Regent House, 5 Regent street, London, England, have invented and produced a new and original Design for Metallic Wheel-Rims, of which the following is a specification, reference being had to the accompanying drawings, forming part thereof.

This invention relates to a new and original design for metallic wheel-rims.

In my design the leading feature consists in the form of the wheel-rim, which has a flat base with sides so formed that the distance between the edges *a* of the sides is approximately as great as the width of the out-

side *b* of the flat base, said sides being V-shaped and the parts *c* and *d* thereof being of approximately equal length. 20

In the accompanying drawings, Figure I represents a cross-sectional view of the wheel-rim, and Fig. II shows the wheel-rim in perspective.

What I claim is—

The design for a metallic wheel-rim, substantially as herein shown and described.

In testimony whereof I have hereunto set my hand, in presence of two subscribing witnesses, this 1st day of June, 1900.

JAMES MECREDY MACLULICH.
